Primary Examiner — Paula Allen Greene*(74) Attorney, Agent, or Firm* — NSIP Law(57) **CLAIM**

We claim the ornamental design for an earphone, as shown and described.

DESCRIPTION

FIG. 1 is a front perspective view of an earphone showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a rear perspective view thereof; and,

FIG. 9 is a front view thereof in which a symmetric earphone and cable are provided in broken lines to illustrate an example environment.

The broken lines in the figures depict environmental subject matter and form no part of the claimed design.
